CLAIM

The ornamental design for the metal insert for carpentry, as shown and described.

DESCRIPTION

FIG. 1 is an upper perspective view of the metal insert for carpentry showing my new design.

FIG. 2 is a top plan view thereof;

FIG. 3 is a bottom plan view thereof;

FIG. 4 is a side elevation view thereof, an opposite side elevation view, front view and back view being identical to FIG. 4;

FIG. 5 is a side elevation view thereof, showing an alternative embodiment with length being the variable; and,

FIG. 6 is a perspective view, showing insertion into a plank. The metal insert for carpentry is used in construction. The broken lines in the drawings represent environmental subject matter and form no part of the claimed design.
